CLAIM

The ornamental design for a container with cap, as shown and described.

DESCRIPTION

FIG. 1 is a front isometric view of a container with cap showing my new design;

FIG. 2 is a left side elevational view;

FIG. 3 is a fragmentary right side view of the bottle and cap shown in FIGS. 1 and 2 wherein the lower portion of the bottle is identical when viewed from all sides;

FIG. 4 is a rear elevational view similar to FIG. 3;

FIG. 5 is a front elevational view similar to FIG. 3;

FIG. 6 is a top plan view; and,

FIG. 7 is a bottom plan view.
